United States Patent Office.

CHAUNCEY O. GREENE AND ROBERT HAM, OF TROY, NEW YORK.

Letters Patent No. 76,910, dated April 21, 1868.

IMPROVEMENT IN BOILERS.

The Schedule referred to in these Letters Patent and making part of the same.

TO ALL WHOM IT MAY CONCERN:

Be it known that we, CHAUNCEY O. GREENE and ROBERT HAM, each of the city of Troy, in the county of Rensselaer, and State of New York, have jointly invented certain new and useful Improvements in Water-Reservoir Stoves and Ranges; and we do hereby declare that the following is a full, clear, and exact description of the construction and operation of the same, reference being had to the annexed drawings, and the letters of reference marked thereon, and making a part of this specification, in which—

Figure 1 is a perspective view, and showing the water-reservoir as in its back or rear position on the stove-top.

Figure 2 is a perspective view, and showing the water-reservoir as turned around to its front position, and over the pot-holes on the stove-top.

Figure 3 is a view of the bottom side of the water-reservoir, showing a friction-flange thereon.

Figure 4 is a top or plan view of a water-reservoir stove, and showing different positions that the water-reservoir may be shifted into, and made to rest in at different times on the stove-top; and

Figure 5 is a vertical longitudinal sectional view of fig. 4.

The same letters refer to like parts in each of the said figures.

The object of our said invention is to produce a water-reservoir stove or range, whereof the water-reservoir may be conveniently and readily changed or shifted around from the cooler to the hotter places, and reversed upon the stove or range-top, and be so operated or moved to that end, without necessity for detaching or lifting said reservoir from the stove or range-top, when so changing its places thereon, for the purpose of regulating the temperature of water within said reservoir to any heat desired, from warm to that of boiling heat; and the nature or distinguishing features of the said invention consist in the water-reservoir of the stove or range being so pivoted or hinged thereto, that the said water-reservoir is made capable of, and it may, without lifting it or detaching it from the stove or range-top, be turned, revolved, or shifted around, or part way around, horizontally, or nearly so, about its pivot-centre thereon, and thereby made to rest upon or over various differently-heated parts of the stove or range-top, at different times, substantially in manner as hereinafter fully described and shown, so that the temperature of water within said reservoir may thereby be regulated from a warm to a boiling heat, as wanted for various culinary and other uses.

The said invention also consists in the construction and combination of certain mechanical devices, substantially as hereinafter fully described and shown, with stove or range-tops and their water-reservoirs, whereby the water-reservoir thereof is secured thereto in such manner as to be easily shifted or moved on and about its pivot-centre, from one position or place to another position or place on said range or stove-top, for the purpose aforesaid.

To enable others skilled in the art to make and use our said invention and improvements, we will now proceed to fully describe its construction and operation, to wit:

In fig. 1, of the annexed drawings, B shows a shifting or turning hot-water reservoir, provided with hinged lids or covers, and mounted upon and hinged or pivoted to the top-plate A of a cooking-stove or range, of construction, in manner, and by devices substantially as follows: In the front side of the water-reservoir B, a recess, G, extending through or from top to bottom, is made or cast therein, and the bottom part or edge of this recess is extended at right angles, or nearly so, to said recess, and inward, so as to form a flange or shoulder, e, concentric with said recess, and fastened by rivets, or otherwise secured to and over, so as to enclose and form the front part or wall of said recess, is an arched plate, D, which has formed on and at its bottom inside face, a section of flange or shoulder, which makes even joint with the flange e aforesaid, and serves to make complete therewith an annular or continuous ring-flange, e, at the bottom of said recess G, and said flange has made in its back or rear part, a notch, b. The construction and arrangement of the aforesaid devices is fully shown in figs. 3, 4, and 5, of annexed drawings. There is formed on or attached to the front of the pipe-collar h, of the exit-passage C, a holding-lug, a, projecting laterally or horizontally therefrom, and arranged sufficiently up

from the surface of stove-top A to allow the aforesaid ring-flange e to move freely under said lug a, when adjusted in combination therewith and thereunder.

Formed on or attached to the under side or bottom of said water-reservoir B, is an anti-friction flange or flanges or ribs, g, or suitable equivalent devices therefor, such as friction-wheels or rollers; or the said anti-friction devices may be attached to the stove or range-top A, instead, and effect their purpose, but we prefer them on the bottom of the reservoir, substantially as shown in fig. 3, and arranged thereon concentrically, as shown.

This water-reservoir B, as thus constructed, is now mounted upon the stove or range-top A, as prepared for it, and secured thereon, to operate in combination therewith, by placing it thereon, with its rear or back side square to the front of the stove or range-top, in manner as shown in fig. 2 of annexed drawings, at which position the lug a and the notch b aforesaid are made to coincide, so that the said notch passes the said ring-flange into the proper position for it to move under the lug a, when turning the said reservoir about horizontally in right or in left directions, to shift or change the same about its thus-formed pivot-centre, into different places on the stove-top, within its circle of movement thereon. When the said reservoir is shifted or turned into the position to cover partly the pot or boiler-holes E E, as shown in fig. 2, the lids or covers thereof, and centre-piece F, may be removed, if desired, and a removable cover or hood, I, placed thereon, and joining the reservoir side, and also so as to enclose under it a part of the reservoir's side, and so increase its direct heating-surface. The said fig. 2 shows fully only but a part of said cover I, the rest being shown by dotted lines, to thereby better show the opening closed by said covering-plate. The pipe C, for the exit of the gases of combustion, is placed in the usual manner over the pipe-collar, and is or may be held up thereon by the lug a, or on said lug and a shoulder-support, the collar being made somewhat higher than is customary, so as to serve also as a pivot-centre as aforesaid, for the water-reservoir B, which shifts or turns thereabout, without support of or contact with said exit-pipe.

This new improved water-reservoir stove or range is managed or operated to effect its purpose of heating water therein to any intermediate temperature, from warm up to a boiling heat, inclusive, in manner as follows: For warm water only, change or shift the water-reservoir B, by turning it about its pivot-centre, into its least hot place, as in rear of the exit-pipe C, and on the back end of the stove or range-top, in manner as shown in fig. 1. When water still warmer is wanted, but not of a boiling heat, again shift the said reservoir, by turning it into position lengthwise with the stove-top or side, in manner as shown by the black lines in figs. 4 and 5; and when boiling-hot water is wanted, the said reservoir is then to be shifted or turned on and over the hottest place for it on the said top, and in position as shown in fig. 2, in which position the water therein is made boiling hot. The blue and red lines in said fig. 4 show other and some of the intermediate positions on the stove or range-top, into which the said water-reservoir B may be shifted or changed, by turning it about its pivot-centre, in manner as aforesaid.

The said water-reservoir, in its shifting or changing movements from one position to another on and about the stove or range-top, moves at all times easily, and with little friction thereon, and on and about its pivot-centre, because the aforesaid friction-flange or flanges on the reservoir-bottom present but small surface of contact with and on the stove or range-top, and with the leverage obtained by applying the moving force at the end or ends of the water-reservoir, and when the stove or range-top is occasionally blacked over with plumbago or "black lead," so overcomes and lessens friction, that the said water-reservoir or tank is moved easily thereabout, when brimful of water.

What we claim as our invention, and desire to secure by Letters Patent, is—

1. In combination with a cooking-stove or range, we claim a water-reservoir or boiler, B, when hinged or pivoted to or upon said stove or range-top, in manner such that the said water-reservoir or boiler may be turned, revolved, or shifted thereon about its pivot-centre, and thereby be made to rest upon or over the differently-heated parts of said stove or range-top, to thereby increase or decrease, or regulate the temperature of water within said reservoir or boiler, substantially in manner as hereinbefore described and shown for the aforesaid purpose.

2. In combination with a cooking-stove or range, we claim the arrangement of the exit-passage or flue thereof, for the gases of combustion, and the said pivoted, turning, or shifting water-reservoir, both at one and the same end of said stove or range, in manner substantially as described, so that the escaping gases of combustion thereout shall impart heat to said water-reservoir, in any one of its shifted positions on and over the stove or range-top, as set forth.

3. We claim a cooking-stove or range, having a top-plate provided with pot-holes, E, and a water-reservoir, B, so mounted and pivoted thereon that it can be turned or shifted horizontally about its pivot-centre, as described, and placed over or partly over the said pot-holes, so as to receive the greatest heat from the stove or range, and also be turned off horizontally, to leave the said pot-holes exposed or open and free, to place culinary vessels therein, as set forth.

4. We claim, in combination with a stove or range-top, pot-holes E and a water-reservoir, turning or shifting about its pivot-centre thereon, as described, a loose and removable cover-plate or hood, I, substantially as and for the purpose set forth.

5. We claim the manner of securing said pivoted and shifting reservoir to the stove or range-top, by means of the collar h, with lug a, and flange-ring e, with notch b, or any equivalent devices therefor, which shall hold the said reservoir upon the stove or range-top, so that it may turn about its pivot-centre, as described, and keep it securely thereon, in any one of its shifted positions on and about its pivot-centre, as set forth.

6. We claim, in combination with a stove or range, and a water-reservoir moving or shifting about its pivot-centre thereon, as described, a friction-flange or flanges, *g*, or any equivalent devices therefor, formed on or attached to the reservoir-bottom, or to the stove or range-top, as and for the purpose set forth.

CHAUNCEY O. GREENE,
ROBERT HAM.
